UNITED STATES PATENT OFFICE.

JOHN E. BOLLING, OF CHICAGO, ILLINOIS, ASSIGNOR TO DRYING SYSTEMS, INC., OF CHICAGO, ILLINOIS, A CORPORATION OF ILLINOIS.

LIQUID-FEEDING APPARATUS.

Application filed April 10, 1925. Serial No. 22,049.

This invention relates to liquid feeding devices, and more particularly to vacuum feeding apparatuses for liquid fuel.

The main objects of this invention are to

- 5 provide a vacuum feeding apparatus wherein the vacuum tank is located below the level of the liquid supply; to provide improved means for automatically breaking the siphon between the supply reservoir and the vacuum tank after each operation of replenishing the latter; to provide a vacuum feeding system wherein the customary objectionable float valve has been eliminated from the chamber to which the liquid flows from the 15 vacuum tank; and to provide a vacuum feeding apparatus of this kind which is particularly adapted for use in feeding liquid fuel to the oil burner of a heating plant or similar equipment.

20 An illustrative embodiment of this invention is shown in the accompanying drawings, wherein:

Fig. 1 is a side elevation of a liquid feeding apparatus to which this invention is applied, part of a building being shown in section.

Fig. 2 is a vertical section of a vacuum tank used in carrying out this invention.

Fig. 3 is an enlarged detail of the coupling 30 between the air and liquid passages.

Vacuum feeding systems have long been in general use for lifting liquid from a supply reservoir to a vacuum tank located above the level of the liquid in the reservoir. In 35 such prior vacuum systems the vacuum tank has been arranged to discharge its contents by gravity to a lower receiving chamber, such as a burner, carburetor and the like, and the admission of liquid to the receiving 40 chamber has been controlled by a float valve. Gravity feeding systems have also been in common use for feeding liquid fuel to oil burners and the like wherein a float valve in the receiving chamber has controlled the admission of fuel to the burner. Float valves 45 controlling the admission of liquid fuel to an oil burner are objectionable for many reasons. The heavy fuel frequently causes the float valve to "stick" in its open position, thereby flooding the burner and sometimes causing all of the fuel to be drained from the system before the valve can be closed. Moreover, in fuel feeding systems wherein the admission of fuel to the burner 55 is controlled by such a float valve, the head

of the fuel column varies between comparatively wide limits, thereby rendering constant level conditions at the burner nozzle practically impossible.

In installing oil burning heating systems 60 in old buildings, the supply reservoir, for the sake of convenience, is generally mounted on the floor so as to avoid the labor and expense of sinking it into the ground below the floor level. In such cases, where a vacuum feed 65 has been employed, it has been necessary heretofore to arrange the vacuum tank near the ceiling, or in some other place above the highest level of the liquid in the reservoir, so as to prevent the formation of a siphon 70 in the liquid passage between the reservoir and the vacuum tank. In placing the vacuum tank above the level of the burner or other outlet, it has been necessary to control the admission of fuel to the latter by 75 means of the objectionable float valve.

The above mentioned objectionable features of the vacuum and gravity feeding systems heretofore in use have been overcome by applicant's improved liquid feeding apparatus, which avoids the use of a float valve 80 at the burner or other receiving chamber, and which maintains a substantially uniform head on the liquid at the nozzle or other outlet.

In the specific form of applicant's improved liquid feeding apparatus herein shown, the liquid is drawn from a main supply reservoir to a vacuum tank located below the level of the liquid in the reservoir. 90 The vacuum tank is constructed so that the liquid level of its storage compartment varies only slightly during the operation of the device, whereby the level of the liquid at the burner nozzle or other outlet is substantially 95 constant. In order to break the siphon which forms between the supply reservoir and the vacuum tank while the latter is being replenished, means is provided for automatically admitting air to the liquid passage 100 at a point above the highest liquid level of the system.

In the construction herein shown, the invention is applied to an oil fuel feeding apparatus, including a main supply reservoir 1, and a vacuum tank 2 located below the liquid level of the reservoir, and connected to an exhaust pump 3 and a burner nozzle 4. As shown in Fig. 1, applicant's invention permits the reservoir 1 and vacuum tank 2 110

to be both supported near the floor 5 of a building, represented at 6. A filler pipe 7 extends from the reservoir 1 to a window 8, so as to facilitate filling of the reservoir.

5 The usual vent pipe 7.1 also extends from the reservoir to a point outside of the building.

The vacuum tank herein shown comprises the usual vacuum compartment 9, arranged 10 to discharge its liquid contents by gravity to an outer supply compartment 10 through a passage 11 controlled by the usual flap valve 12, which is arranged to be opened by the 15 gravity flow of the liquid when the suction compartment 9 is restored to atmospheric pressure.

The suction compartment 9 communicates 20 with the supply reservoir 1 through a liquid passage or conduit 13, and with the exhaust motor 3 through a suction conduit 14. A vent tube 15 forms the usual atmospheric relief. The suction conduit 14 and vent tube 15 are controlled by valves 16 and 17 respectively, which are connected by levers 18 25 and 19 and link 20 to a float 21, so that the suction compartment 9 will be alternately connected with the exhaust means 3 and with the atmosphere, as is well understood in the art.

30 The outer compartment 10 communicates with the vent tube 15, through an air passage 21, and communicates with the burner nozzle 4 through a conduit or liquid passage 22. The outer compartment 10 is considerably 35 larger in diameter than the inner compartment 9, so that, when the liquid in the latter is discharged into the former the liquid level in the outer compartment is varied only slightly.

40 After a flow of liquid from the reservoir 1 to the vacuum tank 2 has been started by the suction in the compartment 9, a siphon forms in the liquid passage 13 which, if not broken, would continue until the entire reservoir had been drained. The improved 45 means herein shown for breaking the siphon comprises an air tube 23, which is arranged to automatically direct air from the compartment 9 to the liquid passage 13, at a 50 point above the highest level of the liquid in the system when the float 21 has been lifted sufficiently to open the air valve 17 and close the suction valve 16. The lower 55 end of the air conduit 23 is connected to the top of the vacuum tank, as shown in Fig. 2, and the upper end thereof is connected to a coupling 24, which is arranged in the air 60 passage 13, and which is located at a point above the mouth of the filler pipe 7. In order to prevent the liquid in the passage 65 from entering the air passage 23, a short tube 25 is arranged within the coupling 24 so as to direct the liquid beyond the upper end of the air pipe 23. This tube 25 is of 70 considerably less diameter than the coupling

24 so as not to interfere with the admission of air to the liquid passage in breaking the siphon.

The burner nozzle 4 is located slightly above the highest level of the liquid in the 70 compartment 10 of the vacuum tank so that the liquid in the conduit 22 is readily drawn into the nozzle by the air which is forced through the burner, or as readily fed to an 75 oil pump or other device.

In operation, in the lowermost position of the float 21, the vacuum chamber 9 is in communication with the exhaust pump 3 which closes the valve 12 and draws liquid from the reservoir 1 to the float chamber 9. When the float 21 rises to a predetermined level, the chamber 9 is restored to atmospheric pressure by the closing of the valve 16 and the simultaneous opening of the valve 17. The air in the chamber 9 is then directed through the passage 23 to the coupling 24 so as to break the siphon in the liquid passage 13. When atmospheric pressure is restored to the chamber 9, the liquid 80 therein passes downwardly through the passage 11 to the compartment 10. The liquid level in the compartment 10 varies only slightly between consecutive operations of the device so that the liquid in the conduit 22 is maintained at a substantially constant 85 level.

Although but one specific embodiment of this invention has been herein shown and described, it will be understood that numerous details of the construction shown may be altered or omitted without departing from the spirit of this invention as defined by the following claims:—

I claim:

1. In a liquid feeding apparatus, the combination with a supply reservoir adapted to contain a liquid, of a receiving chamber, a liquid passage adapted to provide siphonic communication between said reservoir and chamber and extending above the highest liquid level of said reservoir, mechanism adapted to intermittently force liquid through said passage to said receiving chamber, an air passage communicating with said liquid passage at a point between the highest liquid level of said reservoir and the highest part of said liquid passage, a deflector arranged within said liquid passage adjacent the air inlet port for preventing liquid from entering said air passage, and means controlled by the level of the liquid in said chamber for opening said air passage to the atmosphere to break the siphon in said liquid passage.

2. In a liquid feeding apparatus, a vacuum tube, a reservoir, a siphon connection from the tank to the reservoir, means for exhausting the air in the tank, means governed by the amount of liquid in the tank for alternately opening and closing the

tank, said siphon connection having an air chamber in the downflow side located above the highest level of fluid in the reservoir, said chamber opening downwardly into the stream of fluid, and a pipe connection from the tank to said chamber.

3. In a liquid feeding apparatus, a vacuum tank, a reservoir, a siphon connection from the tank to the reservoir, means for alternately exhausting the tank and opening the tank up to the atmosphere, a cou-

pling in the downflow side of said siphon connection located above the highest fluid level in the reservoir, said coupling having a downwardly projecting nozzle providing an air chamber shielded from the stream of the liquid, and a pipe connecting the tank to said chamber. ¹⁵

Signed at Chicago this 4th day of April, 1925.

JOHN E. BOLLING.
